Patented May 9, 1961

190,290

WATER POWERED KNIFE SHARPENER

Bernard H. Swanson, 903 Queens Lane, Anoka, Minn.,
and Clifford W. Hutchinson, 3121 Washington Ave. N.,
Minneapolis, Minn.

Filed Oct. 17, 1960, Ser. No. 62,509

Term of patent 14 years

(Cl. D37—1)

Figure 1 is a side elevational view of a water powered knife sharpener, showing our new design.

Figure 2 is a side elevational view thereof directly opposite to that of Figure 1.

Figure 3 is a front view thereof.

Figure 4 is a rear view thereof.

Figure 5 is a top plan view thereof.

Figure 6 is a bottom plan view.

We claim:

The ornamental design for a water powered knife sharpener, as shown.
